PUMP CONSTRUCTION

Francis L. Dieterich, Los Angeles, Calif.

Application August 30, 1935, Serial No. 38,567

6 Claims. (Cl. 103—202)

This invention relates generally to pumps of the reciprocating type, and is primarily concerned with means for increasing the useful life of cylinder liners and pistons. It is of particular value in connection with pumps where abrasion and wear upon these parts tends to be severe, as for example in so-called "slush pumps", which are commonly utilized in handling rotary drilling mud for earth drilling operations.

10 It is an object of the invention to provide a novel means in a pump of the above character, for effecting automatic rotation of the pumping piston with respect to its associated liner, as the pump is in operation. It has been recognized in the past that occasional manual turning of the piston tends to prevent channeling and excessive wear between the piston and the liner, although simple and effective means for effecting such turning movement automatically has not been available. The invention as disclosed herein makes use of a novel form of rotator or uni-directional clutching mechanism, which rotates the piston of the pump a small angular increment during each complete cycle, and which is capable of long useful life without mechanical failure.

Another object of the invention is to provide a mechanism of the above character, which can be readily applied as an attachment to conventional slush pumps, to effect the results desired.

30 Additional objects of the invention will appear from the following description in which the preferred embodiment of the invention has been set forth in detail in conjunction with the accompanying drawings.

35 Fig. 1 is a side elevational view, partly in cross-section, illustrating a pump of the direct acting steam type which is equipped with the present invention.

Fig. 2 is a side elevational detail, in cross section, illustrating the uni-directional rotating mechanism which is incorporated with the pump of Fig. 1.

Fig. 3 is a plan detail, illustrating the guide track employed in effecting actuation of the rotating mechanism.

Fig. 4 is a cross sectional detail taken along the line 4—4 of Fig. 2.

Fig. 1 illustrates a representative type of slush pump, having a reciprocating steam driving unit 10, directly connected to a pumping unit 11. While it is needless to describe conventional details of this equipment, it may be briefly pointed out that the driving unit includes a piston 12 operating within the steam cylinder 13, and connected to the reciprocating piston rod 14. The

pumping unit includes the piston 16, operating within cylinder 17, and connected to the reciprocating piston rod 18. The adjacent ends of piston rods 14 and 18 are customarily connected together by a cross head 19, thereby establishing a rigid connection between the pistons 12 and 16. Likewise crosshead 19 is customarily engaged by the lower end of a valve operating arm 21, which operates the steam admission and exhaust valve 22, through the valve operating gear 23.

Assuming that the invention to be presently described is not utilized, the pumping piston 16 and its associated cylinder lining 24, are subject to rapid deterioration. Repeated reciprocating movements of the pumping piston causes a progressive development of score lines upon the inner walls of the liner, to the point where a certain amount of the fluid being pumped by-passes or channels between the piston and the liner. After such channeling has commenced, the score lines or grooves increase in depth at a rapid rate, until the efficiency of the pump is impaired to such an extent that replacement of the worn parts is necessary. For the most part such scoring and channeling is responsible for rapid deterioration of the piston and liner, although some deterioration is caused by the direct abrasive action of gritty components, such as sand, in the rotary mud or like liquid being handled. Occasional manual turning of piston 16 may prolong the life of the piston liner, although such manual attention cannot occur at sufficiently frequent intervals or be carried out in such a manner as to produce results comparable to the present invention.

In the present invention rotating mechanism is provided which rotates the pumping piston by a small increment as the piston moves in one direction, while during the return stroke the piston is permitted to move straight or without turning movement. Thus there is a cross wearing action between the piston and the liner, which prevents the formation of straight score lines or grooves, and which causes a polishing or lapping rather than a grooving of the liner and piston. Instead of utilizing a ratchet and pawl mechanism, which might produce an undesired periodicity of turning movement for the successive strokes, I employ uni-directional mechanism which permits small and properly controlled turning increments, and which will make possible the desired polishing or lapping action.

In incorporating my invention as an attachment to a pump of the type described above, a special cross head 19 is substituted for the common type of cross head with which such pumps

are commonly equipped. Thus referring to Figs. 2 to 4 inclusive, the cross head which I substitute consists of a body 26, having annular end flanges 27, and which is rigidly secured to the adjacent 5 ends of piston rods 14 and 18, by suitable means such as the thread connections 28. Each of the end flanges 27 are provided with annular recesses, upon which rings 31 are journaled. These rings in turn are secured to end plates 32, which constitute two branches of a yoke 33. For the purpose of oscillating yoke 33, a guide track 36 is provided, which can be readily attached to the pump bed 37. One suitable form of attachment is illustrated in Fig. 4, in which a 15 guide track 36 carries lateral extensions 38, which engage the parallel bed portions 39. Clamps 41 engage the under sides of bed portions 39, to retain the guide track rigidly in place. By reference to Fig. 3, it will be noted that the guide track 20 36 extends at an angle to the axis of the aligned piston rods 14 and 18. The operating engagement between yoke 33 and guide track 36, may consist of a roller 42, journaled by ball bearings upon the yoke extension pin 43.

25 The uni-direction mechanism, which is built into the cross head, is illustrated in Fig. 4. Thus within one of the rings 31, the body 26 is provided with segmental and tapered recesses 44, which accommodate the segmental wedges 47. 30 Each of these wedges is urged in one direction, by a compression spring 48. It will be evident by reference to Fig. 4 that yoke 33, in conjunction with ring 31, may swing in a clockwise direction. However, a swinging movement in a counter-clockwise direction causes a jamming action of 35 wedges 47, with the result that the body 26 of the cross head is likewise caused to rotate, to rotate both of the piston rods 14 and 18.

40 Operation of the invention described above can now be outlined as follows:—When the pump piston 16 moves to the left, as viewed in Fig. 1, the yoke 33 (as viewed in Fig. 4) is swung in a clockwise direction, and therefore the piston rods and the associated pistons are not rotated. However, on the return stroke, swinging of the yoke 45 33 causes a small angular turning movement of the piston rods and associated pistons, this turning movement being distributed over the entire return stroke. Thus the pumping piston 16 is currently turned by small increments during 50 operation of the pump, to secure a lapping action with respect to the liner 24, and to evenly distribute wear.

55 It is characteristic of the uni-direction mechanism illustrated in Fig. 4 that it will afford long reliable service, commensurate with the life of a pump of this character. Large areas of contact are provided between the segmental wedges 47 and the adjacent surfaces of the ring 31 of the cross head body, and there is no tendency towards sticking and jamming. Likewise by means of 60 mechanism of this character the increments of turning movement is so adjusted that there is virtually no recurrence of periodicity of scoring action on the same points of the piston and liner. In other words there may be a true overlapping

action, such as will best promote the life of the piston and liner.

I claim:

1. In a pump, a pumping cylinder, a piston having reciprocating movement within the cylinder, a piston rod connected to the piston, and means including a guide track extending generally in the direction of the axis of the piston rod, for turning the piston by small increments during each stroke of the piston in one direction. 10

2. In a pump, a pumping cylinder, a piston having reciprocating movement within the cylinder, a piston rod connected to the piston, an arm carried by the piston rod for swinging movement relative to the rod, a relatively stationary guide track engaged by said arm and serving to swing the arm as the piston rod is reciprocated, and uni-directional turning mechanism operating between said arm and the piston rod.

3. In a pump, a pumping cylinder, a piston having reciprocating movement within said cylinder, a piston rod connected to the piston, an arm adapted to have swinging movement in a plane substantially normal to the axis of the piston rod, and uni-directional turning mechanism operating between the arm and the piston rod. 20

4. In a pump, a pumping cylinder, a piston having reciprocating movement within said cylinder, a piston rod connected to the piston, a cross head to which the piston rod is connected, an arm 30 journaled to the cross head and adapted to having swinging movement in a plane substantially normal to the axis of the piston rod, and uni-directional turning mechanism operating between the arm and the piston rod.

35 5. In a pump, a reciprocating pumping piston, a reciprocating driving piston, a pair of aligned piston rods connected to said pistons, a cross head serving to connect the adjacent ends of said rods, an arm carried by said structure and extending laterally from the same, said arm being free to swing in a plane substantially at right angles to the axis of said rods, means for effecting swinging movement of said arm responsive to reciprocation of said structure, and a uni-directional 45 clutching mechanism acting between said arm and said structure and serving to turn the piston rods in one direction.

6. In a pump, a reciprocating pumping piston, a reciprocating steam piston, a pair of aligned 50 piston rods connected to said pistons, a cross head serving to connect the adjacent ends of said rods, said cross head serving to transmit motion to steam valves, an arm carried by said cross head for swinging movement in a plane generally at 55 right angles to the axis of said rods, a stationary guide track engaging said arm, said guide track serving to cause limited swinging movement of said arm responsive to reciprocation of said cross head, and uni-directional clutching mechanism 60 acting between said arm and said structure, whereby said structure is caused to rotate responsive to reciprocation of the same, to effect rotation of the pumping piston.

65 FRANCIS L. DIETERICH.
